HEINRICH BECK, OF SCHENECTADY, NEW YORK, ASSIGNOR TO GENERAL ELECTRIC COMPANY, A CORPORATION OF NEW YORK.

SEARCH-LIGHT ARC-LAMP.

1,313,666.

Specification of Letters Patent.

Patented Aug. 19, 1919.

Application filed June 15, 1916. Serial No. 103,881.

To all whom it may concern:

Be it known that I, HEINRICH BECK, a subject of the German Emperor, residing at Schenectady, in the county of Schenectady 5 and State of New York, have invented certain new and useful Improvements in Search-Light Arc-Lamps, of which the following is a specification.

My invention has reference primarily to 10 improvements in searchlights, projectors or other like apparatus designed for directing a beam of light outwardly and in which the source of light is an arc lamp; but some of the improvements are applicable to arc 15 lamps used for other purposes. The aim of the invention is to render the operation of an arc lamp with a large current more secure and uniform, to start the arc and regulate the same automatically by electrical and 20 mechanical devices that may be largely contained within a searchlight casing, and, in addition thereto, to provide means for continuing the control of the arc in case some of the electrical means provided for this 25 purpose, should, for any reason, fail to properly perform the functions assigned to the same.

In the accompanying drawing only the 30 essential part of the mechanism now employed in practice is broadly indicated as follows:

Figure 1 is a diagrammatic view of the 35 arc controlling mechanism as a whole and of the circuit connections; Fig. 2 is an end view, upon a somewhat larger scale, of the anode head or holder, and Fig. 3 is a vertical section of the feed pin coupling.

The anode and cathode are indicated 40 respectively at 1 and 2, and these electrodes pass through heads or holders 3, 4. The anode is arranged substantially horizontally while the cathode is inclined at an angle, with its arcing point directed upwardly. When the apparatus is not in operation the 45 electrodes are separated as shown, and for starting the arc they have to be first brought into contact and then again separated. The electrodes are continuously rotated each about its own axis and are fed toward each 50 other to compensate for their consumption. The rate of the forward feed of the cathode is determined purely mechanically while the rate of the feed of the anode is normally controlled electrically by a thermostat, and 55 only when the latter fails is the feed of

the anode determined purely mechanically. The rotation of the electrodes about their axes is effected by the rotation of their heads or holders 3, 4 by suitable gearing which is actuated by an electric motor and by the 60 rotation of the heads, and in coöperation with mechanism which at the proper times enters into and modifies the operation of the heads, the electrodes are fed forward to compensate for consumption. The arc is 65 established by another electric motor, which propels the head or holder of the cathode forwardly until the cathode makes contact with the anode and then withdraws it from the same. There is, thus, one electric motor 70 which controls the rotation of both electrodes about their axes and influences the feed of the electrodes and this motor I call the feed motor; and there is another electric motor whose sole function is to establish the 75 arc, and this motor I call the arc establishing motor. This, in broad outline, is the mode of operation of my system, and the sequence of these operations and the means by which the sequence is determined I shall 80 now describe in greater detail.

Current is supplied to the apparatus by the mains 5, 6, by closing the main switch 5', and these mains are kept at a constant difference of potential by the distant generator. As a rule this difference of potential is about 120 volts. In the negative main 6 there is a rheostat 7 by which the current admitted to the arc is regulated; for searchlights the current employed may be as low 90 as 60 amperes and as high as 300 amperes. A subsidiary negative main 6' shunts the rheostat and these three mains must be understood to be connected with the circuits entering the searchlight by some flexible or 95 sliding connections which do not interfere with the turning of the searchlight in azimuth or in a vertical plane. These are appliances that are well understood in the art and it is therefore not necessary to illustrate 100 the same. Moreover, since my invention is applicable to arc lights used for other purposes than searchlights, the connections of the circuits entering the apparatus with the mains is in the drawing indicated as fixed. 105 The main branch which enters the apparatus from the mains is indicated by the conductors 8, 9 and these are here shown diagrammatically as connected directly to the anode and cathode respectively; it will be under- 110

stood, however, that in actual practice suitable clamps are employed.

To the feeding motor 10 passes the branch 11, 12 with a normally closed switch 13 in 5 one of the branch wires and which may be opened by the operator by depressing a button, as indicated. This motor 10 is a shunt motor as is indicated by the connection of its field magnet 14. The shaft 15 of the armature 16 of this motor carries a miter wheel 17 which meshes with the miter wheel 18 whose vertical shaft 19 carries two other miter wheels 20, 21, the former meshing with the miter gear 22 and the latter with the 15 much larger miter gear 23, which forms a part of the head or holder 3 of the anode; and by this connection the head 3 is rotated in a bearing which is conveniently indicated at 32°. The miter gear 22 is at one end of a 20 countershaft 24 at the other end of which is a miter gear 25 meshing with the miter gear 26 on a vertical shaft 27 which, at its upper end, has a miter gear 28 meshing with the much larger miter wheel 23' which is a part 25 of the head or holder 4 of the cathode; and by this connection the cathode head is rotated.

The countershaft 24 is made in two parts which are connected by a coupling 29, to 30 which the left hand part of the countershaft is secured by a pin 30 or in any other suitable fashion. This coupling receives in an axial bore the right hand part of the countershaft so that it can freely slide therein, 35 and a pin 31 from this part of the countershaft passes through a slot in the coupling so that while this right hand side of the countershaft can freely slide within the bore of the coupling the pin clutches the latter 40 to the countershaft so that it has to turn with the same. The system of gearing herein described for rotating the electrode heads 3, 4 may of course be changed in a variety of ways without departing from my invention.

45 The miter gears 25, 26 are journaled in a casting 32 through the main body of which passes the screw threaded portion of the elongated shaft 33 of the armature 34 of the starting motor; and a toe 35 downwardly 50 extending from the casting 32, is located between the two switch levers 36, 37 so that when the casting 32 is moved horizontally the toe 35 engages with one or the other of these switch levers for a purpose which will 55 appear farther on. The switch levers 36, 37 are near the upper ends connected by a spring 38 and the lower ends of these switch levers are in operative relation to three 60 spring contacts 39, 40, 41. The spring contacts 39 and 41 are connected by a bridge wire 42 and this bridge wire is connected by a conductor 43 with the positive main 5 and the spring contact 40 is connected with the subsidiary negative main 6' by a conductor 44.

The starting motor has two field magnets. One of these, 45, has one of its terminals connected with the switch lever 37 by conductor 46 and the other terminal is connected with the back contact 47 of the armature 48 of an electromagnet 49, while the front contact 50 is connected with the switch lever 36 by a conductor 51. The armature 48 is normally raised into engagement with the back contact 47 by a spring, as indicated. 70 The armature 48 is connected with one commutator brush of the armature of the starting motor by a conductor 52. The other field magnet 53 of the starting motor is connected with the branch conductors 54, 55 80 which are tapped to the negative main 6 and the subsidiary negative main 6' respectively. The conductor 55 is connected to the second brush of the armature of the starting motor through a hand switch 56 which is normally 85 in a closed position as shown. The winding of the electromagnet 49 is in a branch derived from the conductors 54 and 55.

The mechanism and circuit connections so far described coöperate in starting the arc 90 and rotating the heads 3, 4 as follows:

When the main circuit is closed by the main switch 5', the rheostat lever is understood to be in a proper position to admit the requisite amount of current to the electrodes, 95 which at that time are separated as shown in the drawing. The normal distance apart of the tips of these electrodes is supposed to be that which is indicated by the dotted line extension at the anode 1. Current is 100 started through the feeding motor 10, through the conductors 8, 12, and by the system of gears hereinbefore described this motor actuates the heads 3, 4 which are thus rotated each about its own axis. The switch 105 levers 36, 37 are at this stage in contact with the spring contacts 40, 39, respectively, and the circuit thereby established is as follows: from the positive main 5 to the branch conductor 43, bridge wire 42, spring contact 39, 110 switch lever 37, conductor 46, downwardly through field magnet 45, back contact 47, armature 48, conductor 52 to and through the armature 34 of the starting motor and by the closed switch 56, and conductor 55 to 115 the subsidiary negative main 6'. The motor in this condition operates therefore as a series motor. At this time the second field magnet 53 of the starting motor is in a dead loop since its terminals are connected with 120 the negative main 6 and with the subsidiary negative main 6'. There being no current yet flowing through the negative main, there can be none diverted to the field 53. At this time, too, the electromagnet 49 is in a dead 125 loop for the same reasons. By the rotation of the armature 34, its screw threaded shaft operates to propel the casting 32 and with it, the connected gears 25, 26, 28 and 23' toward the right, it being understood that all 130

these parts are so held together that they all have to move as one, as for instance by a standard 32^a rising from the casting 32 and having a bearing 32^b for the head 4, and 5 suitably located lugs 32^c as guides for the shaft 27 and for the rod 75'. The coupling 29 between the two parts of the countershaft 24 freely permits this movement. Eventually the cathode makes contact with the 10 anode and current now flows by the conductors 8, 9 between the contacting electrodes. By this time the toe 35 of the casting 32 has not only moved toward the right to free the switch lever 36 to the action of the 15 spring 38 whereby contact between this switch lever and the spring contact 40 is broken, but the toe is now far enough to the right to allow the spring 38 to carry the switch lever 36 over into contact with spring 20 contact 41, but the toe is not sufficiently far to the right to bear upon switch lever 37 so as to break contact between the latter and spring contact 39. At the same time the winding of electromagnet 49 is placed in 25 a live circuit shunting the resistance of the rheostat 7 by conductors 54, 55 and taking current corresponding to that resistance, since now the negative main 6 carries the return current from the electrodes. The 30 armature 48 of this electromagnet is therefore attracted and bears upon the front contact 50. This establishes a new circuit for the starting motor as follows: from the positive main 5 by branch conductor 43, bridge 35 wire 42, spring contact 41, switch lever 36, conductor 51, front contact 50, armature 48, conductor 52, to and through the armature 34 of the starting motor and by closed switch 56 at the point 57 to the branch conductor 40 55, and to the subsidiary negative main 6'. The field winding 53 now receives current by the branch conductors 54 and 55, shunting the resistance of the rheostat 7, just as described with reference to magnet 49. The 45 starting motor, therefore, now operates as a shunt motor and it will be observed that the current through its armature passes in the same direction as before while the current through the field 53 passes in a direction opposite to that which has been traced through the field magnet coil 45; the motor is therefore reversed and the casting 32 with its connected gearing and with the head 4 are now moved toward the left hand side, thereby 50 starting the arc, and this reverse movement continues until the toe 35 encounters the switch lever 36 which breaks contact with spring contact 41 and establishes contact with spring contact 40. By this time the arc 55 has attained about its normal length and while the live circuit of the starting motor as a series motor is now interrupted at back contact 47, and as a shunt motor at spring contact 41, it has attained a considerable speed, which, if allowed to continue would

separate the electrodes beyond the normal length of the arc. But the rotation of the motor armature is checked by the fact that it is now on a short circuit, closed upon itself by that part of the auxiliary negative main 70 which extends between the junctions with the same of the branch conductors 44 and 55. The motor thus becomes a generator and acts as an electromagnetic brake upon itself. 75

From the foregoing it will be seen that as the casting 32 with its toe 35 and the other parts connected therewith is by the starting motor, acting as a series motor, propelled toward the right, the switch lever 36 is freed 80 to make contact with the spring contact 41 at the moment when contact between the electrodes is established. At that moment three things occur simultaneously, namely, current starts in the branch 8-9 so that the 85 return current passes through the negative main 6 and consequently the magnet 49 is energized, drawing down its armature 48, which makes contact with contact 50 and thereby converts the starting motor from a 90 series motor into a shunt motor which now operates to withdraw the cathode from the anode, thus establishing the arc, and this arc establishing movement is only interrupted when the toe 35 has caused a break between 95 the switch lever 36 and spring contact 41, whereby, as has been shown, the live circuit of the shunt motor is interrupted and the motor is put on short circuit and acts as a 100 brake upon itself. It will be seen from this 105 that the length of the arc as established by the starting motor when acting as a shunt motor depends upon the position of the toe 35 of the casting 32 with respect to the upper end of the switch lever 36. This 110 necessary relative position, therefore, must be ascertained and established; it is generally different with different sizes of searchlights. It will also be seen that up to the point of operation so far described there 115 is no reason why the switch lever 37 should be movable, since, so far as described, it does not break contact with the spring contact 39; it would, therefore, seem that the contact between these two elements might be 120 fixed. But it sometimes happens that a piece or the whole of either or both electrodes breaks off, or that the electrodes have not initially been adjusted close enough, or that by some mistake no electrodes have been 125 inserted in place before the operation of the arc establishing mechanism is started. When any of these things happens the starting motor, as a series motor, would, even after switch lever 36 has broken contact with the spring contact 40 and made contact with spring contact 41, continue to move the cathode toward the right and jam the electrode heads together and cause injury to either or both heads. In order to guard 130

against this contingency, the element 37 is made as a lever, so that when the casting 32 is moved toward the right beyond the position where it allows the switch lever 36 to part contact with the element 40 and make contact with the element 41, the toe 35 will engage the lever 37 and break its contact with spring contact 39, whereby the starting motor is open circuited and the advance of the cathode toward the anode is stopped before any injury can be done. The switch lever 37, therefore, is a safety switch lever.

The two heads or electrode holders 3, 4 are constructed substantially alike, but the head 4 is in Fig. 1 not shown with all the details that are shown in connection with head 3, but the end views shown in Fig. 2 is a correct illustration of both heads. Therefore, referring now particularly to the upper right hand side of Fig. 1 and to Fig. 2, it will be seen that a worm 58 is journaled eccentrically in the miter wheel 23 by a shaft 59 which also carries a spur wheel 60, and on the same shaft is a pinion 61 which meshes with the internal gear 62. This internal gear 62 is parallel to and concentric with the miter wheel 23 but is journaled independently thereof. To the frame 63 of the head 3, are pivoted two arms 64, 65, in the free ends of which are journaled two gears 66, 67 which mesh with each other. The shaft of gear wheel 66 also carries at its other end a gear 68 which meshes with the worm 58; and between the gears 66 and 68 the same shaft carries a flanged pulley 69 which receives upon its flanges the electrode 1. The shaft of the gear 67 carries a knurled wheel 70, bearing upon the electrode, and a spring 71, connecting the two arms 64, 65, keeps the gears 66 and 67 in engagement with each other and the flanged pulley 69 and knurled wheel 70 in engagement with the carbon which passes between them; the same spring also holds the gear 68 in engagement with the worm 58.

The operation of the heads 3, 4 of rotating the electrodes about their axes and feeding the same is as follows: The carbon 1 passes through the bushing 72 and between the flanged pulley 69 and knurled wheel 70. When the feeding motor actuates the miter wheel 23 the whole head 3 is rotated and the electrode being held between the pulley 69 and knurled wheel 70 is rotated with the head. The electrode 2 is rotated in the same manner with the head 4, by the miter wheel 23, and need not be further described.

In this operation the spur wheel 60 and the pinion 61 both of which are eccentrically mounted in the head are revolved about the axis of the electrode and thus describe a circular orbit as a part of the planetary gearing. The pinion 61 acting as a clutch upon the internal gear 62 causes the latter to rotate about its own axis which is coinci-

dent with the axis of the electrode; but neither the spur wheel 60 nor the pinion 61 rotates about its own axis; nor does the worm 58, nor the gear wheel 68, nor the gears 66, 67 and flange pulley 69 and knurled wheel 70 rotate about their axes. In other words the electrode is simply rotated about its axis but is not fed forward. But if now by some means, which will presently be described, the spur wheel 60 receives a tangential thrust, it will be rotated about its own axis, that is to say, with its shaft 59 to which pinion 61 and the worm 58 are secured. This worm therefore will now rotate about its axis and actuate the gear wheel 68 and the latter by the shafting and gearing connected therewith will cause the flanged pulley 69 and knurled wheel 70 to rotate each about its axis and thereby propel the electrode forwardly. The tangential thrust upon the spur wheel 60 required for this operation is brought about with respect to head 3 as follows:

There is a little lever 73 mounted on a stationary part of the apparatus and the right hand side of this lever has a spur 73' so located that when the lever is in the position shown in the drawing a pin 74 projecting laterally from the internal gear 62 will freely pass the spur; but if the right hand side of the lever 73 is raised above the position shown on the drawing the pin 74 will, when the internal gear rotates, strike the spur 73' and thus arrest the internal gear. To the left hand arm of the lever 73 is pivoted a pin 75, a finger extension 76 of which rises somewhat above the lever. The lower end of the pin 75 bears upon the left hand arm of a small lever 77 which in turn bears upon a cam 78 which may be adjusted to any desired position by a handle 79 from which an index finger extends over a graduated arc 80, the graduations indicating the position to which the cam has been adjusted. A spring 81 tends to pull down the left hand arm of lever 73 and press the foot of the pin 75 upon the left hand arm of lever 77 and the latter upon the cam or eccentric 78, while the right hand arm of lever 77 is thereby raised against an adjustable nut 82 on a stem 83 extending from the core of an electro-magnet or solenoid 84. By this arrangement the finger 76 can be adjusted to a higher or lower position by turning the eccentric 78 to the left or to the right, respectively, and to these adjustments correspond a lower or higher position of the spur 73', while the core of the solenoid is thereby always held in an elevated or unattracted position. The coil of solenoid 84 is in a branch 85, 86, derived from the arc conductors 8, 9; this branch includes a hand switch 87 and a thermostat 88 composed of the thermostatic strip or strips 89 and contact 90.

An optical system composed of a con-

densing lens 91 and a mirror 92 is arranged with reference to the crater of the anode and the thermostatic strip in such manner that when a certain portion (about 1 millimeter) of the anode has been consumed, the heat rays from the same strike the thermostatic strip, as indicated by the dotted lines 93, 94, whereupon this strip buckles rearwardly as indicated by a dotted line and thereby closes the solenoid circuit; the core of the solenoid is drawn down, the left hand arm of the lever 77 is raised above the eccentric 78 and thereby raises the pin 75 with its finger 76 and depresses the right hand arm of lever 73 still farther out of the path of the pin 74 projecting from the internal gear. In the drawing the solid lines show the condition where the anode has been consumed sufficiently to have its heat rays just thrown upon the thermostatic strip, but it is assumed that the latter has not yet been heated sufficiently to close the solenoid circuit and therefore the core of the solenoid is not shown in its attracted position, and consequently the pin 75 has not yet been raised above the eccentric. The operation of feeding the anode can now be described.

Normally the eccentric 78 is adjusted so that the left hand arm of lever 77 bears upon a somewhat elevated position of the eccentric. This slightly raises the finger 76 but not sufficiently to get into the way of the spur wheel as it describes its circular orbit hereinbefore explained. This is the position of the parts shown in the drawing. When the anode has been consumed to the extent indicated in the drawing so that the heat rays from the crater become concentrated upon the thermostatic strip or strips, the latter, after a second or two, buckle rearwardly and close the branch circuit 85, 86, and thereby the solenoid is energized, the core of the latter is drawn down against the action of the spring 81 and the pin 75 is raised sufficiently to bring its finger 76 into the path of the spur wheel 60. This spur wheel now receives at each revolution of the head 3 a tangential thrust by the finger 76 which enters deeply between its teeth. The spur wheel therefore is now forced to rotate about its own axis, thereby rotates the worm 58 and by the gearing connected therewith the flanged pulley 69 and knurled wheel 70. The anode is therefore propelled forwardly, and it is propelled much faster than is required to compensate for its consumption, until its crater fails to send its heat rays upon the optical system in such direction as to concentrate the heat upon the thermostatic strips. The latter cool rapidly and straighten out to the position shown in solid lines, whereby the branch 85, 86, is opened, the solenoid de-energized and the pin 75 with its finger 76

is drawn down by the spring 81 to the position shown in the drawing while the core of the solenoid is raised also to the position shown in the drawing. This rapid feeding operation is repeated as often as the anode has been consumed sufficiently to direct the heat rays from the crater upon the thermostat. 70

While the operation of feeding the anode to compensate for consumption and restore the focal position of the crater opening, so far described, is the preferable one, it is evident that the mechanism shown lends itself to a slightly different mode of operation which I have also practised successfully. This modified mode of operation is secured by adjusting the cam 78, by turning it slightly counter-clockwise, so that it will raise the left-hand end of lever 77, above the position shown in the drawing and thereby will also raise the pin 75, with its finger end 76, above the position shown in the drawing and sufficiently high to normally be in the way of the spur wheel as it describes its circular orbit and projects slightly between the spurs thereof. With this adjustment it will be seen that at each revolution of the planetary gear there will be impact between the spur wheel and the finger 76, so that the electrode will be propelled periodically forwardly in partial compensation for the consumption which has occurred. In all other respects the operation will be as hereinbefore described, so that when, notwithstanding the slight periodic feed of the anode at each revolution the consumption accumulates sufficiently to require the restoration of the crater mouth to its focal position, the thermostatic system will come into action. These are the normal operations of the feeding of the anode; but if by some accident any considerable forward portion of the anode should break off whereby the arc is broken, a much faster forward feed of the anode is required, in order to reestablish the arc; and this is accomplished by the manipulation of the eccentric by the attendant. He turns this eccentric clockwise and thereby brings its lowest point under the lever 77. 110 The pin 75 is thereby lowered to a correspondingly low position by the spring 81, whereby the right hand arm of the lever 73 is raised sufficiently to bring the spur 73' into the path of the pin 74 projecting from the internal gear. This internal gear is thereby arrested and the pinion 61 which engages it and which continues to describe its circular orbit is rapidly rotated about its axis and rapidly rotates the worm 58. 125 The anode is thereby propelled forwardly with great speed so as to coöperate with the cathode to reestablish the arc in the manner hereinbefore described. As soon as the arc has again attained its normal length 130

and the attendant turns the eccentric counter-clockwise to bring a more elevated point of it under the lever 77 (such, for instance as shown in the drawing) normal feeding 5 operation is periodically resumed.

If by some accident the thermostat should fail to operate, or if for any reason the pin 75 should fail to be raised by the solenoid so as to bring the finger 76 between the 10 teeth of the spur wheel 60 when the normal periodic feed of the anode is required, a periodic feed may be secured by the attendant by turning the eccentric 78 counter-clockwise so as to bring a higher point of 15 the same under the lever 77, whereby the finger 76 is raised to a position in which it periodically enters between the teeth of the spur wheel 60 sufficiently to cause periodic feeding of the anode. This purely mechanical control of periodic feed must be regulated by the attendant to be sufficient to compensate for the consumption of the anode and he can regulate it by turning the eccentric accordingly. This purely mechanical control of feeding of the anode requires intelligent observation of the attendant and this practice is only resorted to in case of a break-down of the thermostatic control; but it is a very important 25 accessory thereto.

The feeding of the cathode is controlled purely mechanically in substantially the same manner as the the periodic feed of the anode when the thermostatic control 30 fails. The pin 75' is by the attendant raised to a sufficient height, by the setting of the eccentric 78', to bring the upper end into the path of the spur wheel, once during each revolution of the head 4, the spring 81' always holding the pin 75' in contact with the 35 surface of the eccentric. The rate of feed of the cathode is primarily determined by the ascertained consumption of this electrode under normal conditions; but this 40 rate of consumption may vary according to the more or less perfect uniformity of this electrode from point to point and if any considerable deviation from the normal rate 45 of consumption develops, the eccentric 78' has to be set to a different point. But it has been found in practice that the variations of 50 consumption of the cathode are insignificant or at any rate of no great importance, since it could only affect the length of the arc; but 55 in searchlights of this character no dependence is placed upon the luminosity of the arc, the real source of light being the crater of the anode. It is therefore the position of 60 the anode in the focus of the reflector which is used in such apparatus that is of importance.

In the operation of feeding the electrodes by the coöperation of the feed pin 75 and the spur wheel 60, it may happen, and it 65 actually frequently happens that the pin

strikes the point of a spur instead of entering between two adjacent spurs. When this happens, the feed pin, if made a rigid structure, may stop the rotation not only of the spur wheel but of the whole head (3 or 4) 70 and thus the feeding operation is interfered with and injury may be done to the mechanism. In order to avoid such accidents and assure regular feeding operation I make the feed pin in two parts, 75^a and 75^b, joined 75 by a coupling 75^c, as shown in Fig. 3. The coupling 75^c is a sleeve into the lower end of which the lower part 75^b of the feed pin is adjustably secured, as by a screw and nut, as shown, while the upper part 75^a of the 80 feed pin loosely passes into the upper part of the sleeve and is guided therein, as shown, by a bushing 75^d and by the bore of the lower part of the sleeve. A pin 75^e passes transversely through the part 75^a and 85 through a transverse slot 75^f in the sleeve, and a coiled spring 75^g holds the part 75^a elevated with the pin 75^e at the upper end of the slot 75^f.

With the special construction of the feed 90 pin here described the feeding operation takes place without hitch, because, when it happens that the feed pin strikes the point of a spur of the spur wheel 60, the upper part 75^a yields to the impact so that the 95 spur wheel clears the point of the pin, while at the next instant when the pin is thrust back to its elevated position by the spring 75^g, the pin may freely enter between two adjacent spurs of the spur wheel. 100

In order to reduce the consumption of the electrodes, to secure the formation of a deep, well formed crater in the anode and for other reasons which it is not necessary here to dwell upon, I use in my searchlight 105 apparatus means for immersing the arcing points of the electrodes and portions behind the arcing points in a non-oxidizing and cooling atmosphere in accordance with my invention set forth in my Patent No. 110 1,029,787 dated June 18, 1912. For this purpose I use ordinarily alcohol vapors directed against the ends of the electrodes by nozzles or burners 95, 96, the vapors being carried to these nozzles by pipe 97 from 115 any suitable source. These vapors of course become ignited and envelop the ends of the electrodes by a flame; but this flame is so very much cooler than the ends of the electrodes that it acts as a cooling agent upon 120 the same. Since this feature is not a part of my present invention it is not necessary to describe it in more detail and a reference to the patent aforesaid is deemed to be sufficient. 125

The details of the mechanism and circuit connections I have herein only broadly indicated and the same can be varied in many ways without departing from my invention. Likewise I have not attempted to 130

show or describe the different parts of the mechanism accurately to scale; these features may be left to the intelligent mechanic. Thus, for instance, the intelligent mechanic 5 will know that in the construction of the feeding pins (75 and 75') the spring 75^g must be much stiffer than either of the springs 81 or 81'. Numerous other features of this kind might be pointed out. Also, it 10 will be understood that the optical system for directing the radiant energy from the crater of the anode upon the thermostat may be variously changed and that in place of a thermostat other devices that are responsive to radiant energy, such, for instance as a selenium cell, may be used.

What I claim as new and desire to secure by Letters Patent of the United States, is:—

1. An arc lamp, comprising a pair of electrodes and controlling and regulating means for the same, constant potential mains connected with the electrodes, a rheostat in one of the mains for controlling the arc current and branches from the mains for diverting 25 to some of the means the potential difference between the mains in advance of or behind the rheostat, respectively, and to others the potential difference across the rheostat.
2. In an arc lamp, a pair of electrodes, constant potential mains connected with the same, a rheostat in one of the mains for controlling the arc current, a motor receiving the full constant potential, gearing actuated by the motor for rotating both electrodes, 30 each about its axis, and for feeding the anode to compensate for consumption, an arc establishing motor for propelling the cathode into contact with the anode, and means for reversing the motor energized by the difference of potential across the rheostat.
3. In an arc lamp, a pair of electrodes, constant potential mains connected with the same, a rheostat in one of the mains for controlling the arc current, an arc establishing motor receiving the full constant potential for propelling the cathode into contact with the anode, and means for reversing the motor energized by the difference of potential 35 across the rheostat when current starts between the electrodes.
4. In an arc lamp, a pair of electrodes, constant potential mains connected with the same, a rheostat in one of the mains, an arc establishing motor for propelling the cathode toward the anode, means for reversing the motor energized by the difference of potential across the rheostat when current starts between the electrodes, and means controlled by a part moving with the cathode 40 for breaking the active motor armature circuit and short circuiting it when the arc has attained the desired length.
5. In an arc lamp, a pair of electrodes

normally separated a definite distance when there is no current on the lamp, an arc establishing motor for propelling the cathode forwardly into contact with the anode, and means controlled by a part moving with the cathode for breaking the motor circuit when by reason of an abnormally large separation of the electrodes the cathode is propelled forwardly beyond the normal distance.

6. In an arc lamp, a pair of electrodes, mechanism for feeding the anode stepwise toward the cathode to more than compensate for the consumption of the former at each step, a normally open-circuited electro-magnet for actuating when energized the feeding mechanism, and automatic means for closing the circuit of the electro-magnet when the anode consumption has reached a pre-determined point.

7. In an arc lamp, a pair of electrodes, means for feeding the anode stepwise toward the cathode to more than compensate for the consumption of the former at each step, a normally open-circuited electro-magnet for actuating when energized the feeding means, a thermostat for controlling the circuit of the electro-magnet, and an optical system for directing the radiant heat from the anode crater upon the thermostat to close the magnet circuit when the anode consumption has reached a predetermined point.

8. In an arc lamp, a pair of electrodes, a rotatable head or holder for each electrode, a motor for rotating each holder about the axis of the corresponding electrode, a planetary gear carried by each holder and geared to the holder for feeding the electrodes to compensate for consumption, and means external to the holders adjustably arranged to intermittently react upon each planetary gear to actuate the same to the desired extent.

9. In an arc lamp, an electrode and holder for the same, means for rotating the holder and electrode about their common axis, a planetary gear carried by the holder and geared with the latter for feeding the electrode to compensate for consumption, means external to the holder adapted to project at one point into the orbit of the planetary gear to actuate the latter once during each revolution, and means for adjusting the depth of projection and thereby the extent of electrode feed.

10. In an arc lamp, an electrode and holder for the same, means for rotating the holder and electrode about their common axis, a spur wheel and worm on a shaft carried by the holder eccentric to the axis of the latter, the worm engaging a system of gears for feeding the electrode to compensate for consumption, a pin adapted to be projected between adjacent spurs of the spur wheel,

and a cam for adjusting the depth of projection.

11. In an arc lamp, an electrode and holder for the same, means for rotating the holder and electrode about their common axis, an internal gear wheel independently rotatable about the same axis, a pinion and a worm on a shaft mounted eccentrically in the holder, said pinion being in clutching engagement 5 with the internal gear and thereby rotating the latter and the worm engaging a system of gears for feeding the electrode to compensate for consumption, and means external to the holder for stopping the internal 10 gear wheel and thereby rotating the pinion and worm shaft to feed the electrode at 15 high speed.

12. In an arc lamp, an electrode and holder for the same, means for rotating the holder and electrode about their common axis, a pinion, a spur wheel and a worm on a shaft mounted eccentrically in the holder, an internal gear independently rotatable 20 about the common axis of holder and electrode, a system of gears in engagement with the worm for feeding the electrode, said pinion being normally in clutching engagement 25 with the internal gear so as to rotate the same, a pin external to the holder adapted to be projected toward the latter 30 between adjacent spurs of the spur wheel, means adapted to be moved by said pin toward and from the internal gear wheel to stop or release the same when the pin is 35 withdrawn from or projected into the spur wheel, respectively, and means for moving said pin to either position.

13. In an arc lamp, an electrode and holder for the same, means for rotating the holder and electrode about their common axis, means for feeding the electrode, electro-magnetic means for actuating the feeding mechanism when the electrode consumption 40 has reached a predetermined 45 point, and hand controlled alternative means for periodically actuating the feeding mechanism.

14. In an arc lamp, an electrode and holder for the same, means for rotating the holder and electrode about their common axis, a spur wheel and worm on a shaft carried by the holder eccentric to the axis of the same, the worm engaging a system 50 of gears for feeding the electrode to compensate for consumption, a pin made in 55 two parts connected by a spring and means for projecting the pin toward the spur wheel for actuating the same whereby when the pin strikes a spur of the wheel it will 60 rebound and then enter between adjacent spurs and turn the wheel about its axis.

15. In an arc lamp, a pair of electrodes and holders for the same, gearing for rotating the anode about its axis, gearing for

rotating the cathode about its axis, a motor 65 for actuating both gearings, a motor for moving the cathode with its holder and gearing toward and from the anode for establishing the arc, and a slidale coupling connecting the two gearings. 70

16. In an arc lamp, a pair of electrodes, a pair of constant potential mains connected with the same, a rheostat in one of the mains for controlling the arc current, an auxiliary main shunting the rheostat, 75 an arc starting motor, circuit connections from the mains and the auxiliary main to the arc starting motor, a system of switches controlled by the motor and a switch controlled by an electro-magnet shunting the rheostat, these switches coöperating to cause the motor to rotate to move the cathode into contact with the anode and then reversing the motor and withdrawing the cathode. 80

17. In a searchlight, the combination with 85 an electrode, of a holder therefor, a rotatable member on said holder for rotating the electrode, means for continuously rotating said member, a feeding device for said electrode including a stop and a member adapted to 90 be moved thereby on rotation of said rotatable member, and means whereby the position of said stop may be varied to alter the feed.

18. In a searchlight, the combination with 95 an electrode and means for rotating the same about its axis, a device for feeding the electrode actuated at periods controlled by the speed of rotation of the electrode, and means for adjusting the rate of feed per 100 period.

19. In a searchlight, the combination with 105 an electrode, of a holder therefor, a rotatable member of said holder for rotating the electrode about its axis, means for continuously rotating said member, a periodically actuating feeding device for said electrode, and means for adjusting the rate of feed per period.

20. In a searchlight, the combination with 110 an electrode, of a holder therefor, a rotatable member on said holder for rotating the electrode about its own axis, a feeding device for said electrode carried by said member, and means for periodically actuating the feeding device and for adjusting the rate of feed. 115

21. An electrode holder for searchlights comprising a body portion, a rotatable member mounted thereon, means for rotating said member, electrode feeding means mounted on said member, a star wheel mounted on said member and connected to said electrode feeding means, a stop capable of adjustment to be normally in or out of 12 the path of said wheel, and means responsive to the position of the electrode tip for governing the position of said stop. 12

22. In a searchlight, the combination with an electrode, of a holder therefor, a rotatable member on said holder for rotating the electrode, means for continuously rotating said member, a stop, a device connected to said member for revolution therewith and adapted to be moved by striking said stop, means

actuated by the said movement of said device for feeding the electrode through the holder, and means whereby the position of 10 said stop may be varied to alter the feed.

It witness whereof, I have hereunto set my hand this 14th day of June, 1916.

HEINRICH BECK.
